UNITED STATES PATENT OFFICE.

FREDERICK W. P. SWINBORNE AND LATIMER P. SWINBORNE, OF LONDON,
ENGLAND.

PROCESS OF MAKING GELATINE.

SPECIFICATION forming part of Letters Patent No. 408,549, dated August 6, 1889.

Application filed November 28, 1888. Serial No. 292,140. (Specimens.)

To all whom it may concern:

Be it known that we, FREDERICK WALLINGTON PFANDER SWINBORNE and LATIMER PFANDER SWINBORNE, manufacturers, subjects of the Queen of Great Britain, both residing at Nos. 33 and 34 St. Andrews Hill, Queen Victoria Street, London, E. C., England, have invented an Improved Process in the Treatment of Hides or Skins to Obtain Gelatinous Matter, of which the following is a specification.

In the specification of an English patent granted to George Philbrick Swinborne, dated the 25th day of November, 1847, No. 11,975, a process is described for obtaining gelatinous matter, consisting in first cutting up hides or skins into thin pieces, treating them with hot water, and afterward evaporating and drying the educt. This process has been largely and continuously used since the date of the patent, and is now well known.

According to this invention, in place of employing the whole of the hide or skin in this process, as has heretofore always been done, we first remove superficial layers from the hair side and from the flesh side, retaining only the middle portion. The cut on the hair

side should be sufficiently deep to remove the grain and hair-roots and that on the flesh side to remove the veins and other impurities. 3c

The drawing shows an edge view of a fleshed skin with the hair upon it, showing the cuts whereby the two sides are removed.

a is the grain and hair-roots, *b* is almost pure gelatine, and *c* is gelatinous substance 35 more or less mixed with fat, veins, flesh, &c. Although the hair is shown in the drawing, it will be understood that the process is equally applicable to unhaired skins.

What we claim is—

The herein-described process of obtaining gelatinous matter, consisting in first removing superficial layers from the hair side and from the flesh side of hide or skin, treating the middle portion (cut into small pieces or otherwise) with hot water, and then evaporating the educt. 45
